Marshall & Hawley,
ATTORNEYS.

UNITED STATES PATENT OFFICE

CHARLES S. ACKLEY, OF BROOKLYN, NEW YORK, ASSIGNOR TO ACKLEY HOLDING CORPORATION, OF NEW YORK, N. Y., A CORPORATION OF NEW YORK

APPARATUS FOR PLACING WAVES IN HAIR

Application filed July 30, 1929. Serial No. 382,091.

This invention relates to apparatus for placing waves in hair.

Waves are usually placed in hair by winding the hair on a suitable rod or tube, applying moisture to the hair, and then applying heat to dry the hair and set the wave. This invention relates more particularly to an oven device or sheath adapted to enclose a coil of hair during the formation of the wave and 10 drying of the hair.

This invention has for its salient object to provide a simple, practical and efficient oven device or sheath for use with hair waving apparatus.

Another object of the invention is to provide an oven device or sheath adapted for use in connection with apparatus for placing a wave or roll in the hair tangent to the scalp.

Further objects of the invention will appear 20 from the following specification taken in connection with the drawings, which form a part of this application, and in which

Fig. 1 is a longitudinal sectional elevation of a device constructed in accordance with the 25 invention, showing a heating rod extending therein;

Fig. 2 is a transverse sectional elevation, on an enlarged scale, taken substantially on line 2—2 of Fig. 1;

Fig. 3 is an elevational view of a sheath or oven constructed in accordance with the 30 invention;

Fig. 4 is a top plan view, on an enlarged scale, of the structure shown in Fig. 3;

Figs. 5 and 6 are sectional elevations, on an enlarged scale, taken substantially on lines 35 5—5 and 6—6 of Fig. 3;

Fig. 7 is a longitudinal sectional elevation, 40 partly broken away, showing the hinge construction of the sheath sections;

Fig. 8 is a transverse sectional elevation showing a slightly modified form of sheath construction;

Fig. 9 is a sectional elevation showing another modified form of construction adapted 45 particularly for use with a marcel waving device;

Fig. 10 is an elevational view of the marcel 50 waving device; and

Fig. 11 shows the oven device illustrated in Figs. 3 to 7 inclusive in use on the scalp.

The invention briefly described consists of an elongated sheath preferably having perforations therein and having a lining of absorbent material, such as asbestos. The sheath is formed in sections adapted to open up to facilitate the removal of and replacing of the lining.

Furthermore, in order to prevent the 60 sheath from contacting with the scalp of the person receiving the wave, when a wave or roll is placed in the hair tangent to the scalp, means is provided on the outer surface of the sheath for insulating a portion thereof. 65

Further details of the invention will appear from the following description.

The form of the invention illustrated in Figs. 1 and 2 is used to place the common form of permanent waves in the hair. In this 70 form of the invention the sheath comprises a pair of sections 20 and 21, hinged together as shown at 22. The section 20 has a pair of catches 23 adapted to snap over projections or protuberances 23' formed at the free edge 75 of the section 21. Each of the sections 20 and 21 has a lining 25 of absorbent material, such as asbestos, secured therein by inwardly projecting lugs 26 and 27. A washer 28 of suitable heat insulating material, such as felt 80 or cork, is carried by the end of the sheath to insulate the sheath from the scalp.

The oven or sheath above described can be used in conjunction with any desired form of apparatus for placing waves in hair but, 85 as illustrated, is used with a tube 30 on which the hair is wound and a heating rod 31 adapted to extend into the sheath and also into the tube. The rod 31 has an enlarged portion 32 adapted to fit within the outer end of the sheath and is also provided with a ring 33 which coacts with clips 34 to retain the rod in the sheath. A handle 35 of suitable insulating material, such as asbestos wood, is provided at the outer end of the rod. 95

In utilizing the apparatus above described, a strand of hair is first wound or coiled around the tube 30 and the tube and coil of hair are then placed within the sheath. The heating rod 31 is then placed in the sheath 100

and tube and the heat from the rod forces the moisture out through the hair. The moisture is absorbed by the lining within the sheath and is gradually dissipated through the wall of the sheath which is provided with perforations 36 for this purpose. The coil of hair may be moistened directly, or absorbent material carried by the tube 30 may be moistened, this moisture being forced outwardly from the head of the rod 31.

The form of the invention illustrated in Figs. 3 to 7 inclusive, and 11, is designed particularly for use in placing rolls or puffs in the hair tangent to or flat against the scalp.

15 In this embodiment, the sheath is provided along a portion of the circumference thereof with suitable heat insulating material, such as asbestos or felt. This material is shown as secured along the longitudinal portions of 20 the sections 21 and 22 adjacent the free edges thereof. One portion of the insulating material is shown at 40 and the other portion at 41.

In order to form a substantially closed oven, 25 each of the sections 20 and 21 is preferably provided adjacent the inner end thereof with a closure plate 37.

The hair is wound on the tube 30 with the tube disposed tangent to the scalp. The 30 heating rod is then placed in the tube and the sheath is then clamped over the tube and rod with the ends of the strand of hair adjacent the scalp extending between the strips 40 and 41 of insulating material (see Fig. 11). The 35 insulating material prevents the sheath from engaging the scalp.

In the form of the invention illustrated in Fig. 8, the sections 50 and 51 are not hinged together but are connected by flanges 52 and 40 53 formed on the section 50, and flanges 54 and 55 formed on the section 51 and interlocking with the flanges 52 and 53. In order to secure the sections 50 and 51 together, the longitudinal edges of the section 50 are 45 sprung inwardly and placed within the longitudinal edges of the section 51. The pressure is then released and the flanges on the sections 50 will interlock with the flanges on the section 51. In order to guide the flanges 52 and 53 into interlocking position, the longitudinal edge portions of the walls of the 50 section 50 are curved outwardly, as shown at 56 and 57.

The form of the invention illustrated in 55 Fig. 9 is substantially the same as that illustrated in Fig. 7, except that the sheath is oval in section instead of substantially cylindrical. This type of sheath is particularly adapted for use with a marcel waving device, shown 60 at 60 in Fig. 9, and described and covered in Patent No. 1,668,836.

From the foregoing description it will be evident that the sheath or oven constructed in the manner set forth facilitates the insertion of and removal of the lining material

and will effectively retain the heat during the baking of the hair to set the wave therein.

Furthermore, the sheath shown in Figs. 3 to 7 inclusive is particularly adapted for use in forming curls or puffs tangent to the 70 scalp.

Although certain specific embodiments of the invention have been particularly shown and described, it will be understood that the invention is capable of modification and that 75 changes in the construction and in the arrangement of the various cooperating parts may be made without departing from the spirit or scope of the invention, as expressed in the following claims.

What I claim is:

1. An oven device for hair waving apparatus consisting of a sheath comprising a plurality of sections having perforated walls, means for securing the sections against separation, and a lining of exposed absorbent material within the perforated walls of said sections.

2. An oven device for hair waving apparatus consisting of a sheath comprising a plurality of sections, means for securing the sections against separation, a lining of absorbent material disposed within and carried by the sections, and heat insulating means carried by and disposed on the outside of said 90 sheath.

3. In combination, a heating rod, an oven device for hair waving apparatus comprising a sheath formed in two sections, means for securing said sections together, and a 100 clip carried by each section and adapted to retain the heating rod in the sheath.

4. A sheath comprising a pair of hingedly connected sections, heat insulating means disposed at the free edges of said sections and 105 along the outer surfaces thereof to protect the scalp from engaging the sheath, and means for securing said edges against separation.

5. A sheath comprising a pair of hingedly 110 connected sections, heat insulating means disposed at the free edges of said sections and along the outer surfaces thereof, and means for securing said edges against separation, said sheath having an exposed lining of absorbent material.

6. In combination, an oven device for hair waving apparatus comprising a pair of sections having closure means at one end thereof, means for holding the sections in closed 120 position, and a heating rod adapted to extend into the other end of the device and substantially close said end.

7. In combination, an oven device comprising a pair of sections, means for securing said sections together, said sections being lined with absorbent material exposed to moisture within said oven device, a heating rod adapted to extend through one end of the device, and means at one end of the device 130

for holding the rod within the device an in spaced relation thereto.

8. In combination, an oven device comprising a pair of sections, means for securing said sections together, said sections being lined with absorbent material exposed to moisture within said oven device, a heating rod adapted to extend through one end of the device, means at one end of the device for holding the rod within the device an in space relation thereto, and means at the other end of the oven device for substantially closing said end.

9. In combination, an oven device comprising a pair of sections, means for securing said sections together, said sections being lined with absorbent material exposed to moisture within said oven device, a heating rod adapted to extend through one end of the device, means at one end of the device for holding the rod within the device and in spaced relation thereto, means at the other end of the oven device for substantially closing said end, and insulating means on the 25 outer surface of said device.

CHARLES SEXTON ACKLEY.
